HERMANN HAMEL, OF DRESDEN-BLASEWITZ, GERMANY

SPINNING MACHINE FOR ARTIFICIAL SILK

Application filed January 27, 1928, Serial No. 249,921, and in Germany February 7, 1927.

My invention concerns a spinning machine for artificial silk with alternately rotating bobbins. For such machines devices are known whereby the bobbin spindles are automatically brought into action, while the switching out of action or reversal of other bobbins is effected by hand.

According to my invention the reversal is effected positively and automatically by an operating shaft which is brought into action at predetermined intervals of time by the driving of the machine whereby it is assured that the bobbins are wound with uniform lengths of thread independently of the attention of the operator.

My invention is illustrated by way of example in the accompanying drawings, wherein

Fig. 1 shows the driving end of a spinning machine in side elevation,

Fig. 2 shows the same driving gear in end elevation, and

Fig. 3 shows to a smaller scale and in diagrammatic form a vertical cross-section through the bearings of the bobbin spindles and the appurtenant driving members.

Fig. 4 is a detail face view of the friction coupling.

Fig. 5 is a side view of the same.

Fig. 6 is a detail with parts in section of the reversing mechanism.

Fig. 7 is a side view of the same.

Fig. 8 is a detail in plan of the slotted lug and pin.

The bobbin spindles 13, 14 are journalled in pairs in a plurality of closed casings 11, 11 which are arranged beside one another on the machine-frame 12, and carry at both ends a bobbin 15. The spindles are mounted in rotatable covers 16 of the casings. The spindles 13, 14 of each box 11 are so arranged that they lie in the same vertical plane. The spindle which lies at the bottom e. g. 13 in Fig. 2, is in this position in engagement with a driving shaft, while the upper spindle is at rest.

After a certain interval of time the spindles are moved round 180°, so that their positions are exchanged.

The driving of the machine is effected from the shaft 17 for example furnished with driv-

ing pulleys, which sets into rotation through toothed gears 18, 19, 20, the shaft 21 which at the same time drives two counter-shafts 23, 24 arranged on either side thereof by means of the pinion 22. The counter-shaft 23 drives a cone pulley 28 through the gears 25, 26, 27. From the wheel 27 through suitable intermediate gears 29, 30, 31 is driven a similar cone pulley 32 arranged with its taper in the opposite direction. With each of the cone pulleys 28, 32 is associated a second cone pulley 33, 34 respectively, the pulley 28 driving the pulley 33 by means of a belt 35 and the pulley 32 driving the pulley 34 by means of a belt 36. During the whole time in which the machine is in operation the two pairs of cone pulleys constantly rotate, the belts 35, 36 being maintained tight in the necessary manner by means of tension rollers not shown. Under the action of a belt guide 38 which is moved to and fro by a screw spindle 37, the two belts move to and fro upon the cone pulleys over an adjustable distance. In the manner hereinafter described the two pairs of cone pulleys act alternately upon the bobbin drive in such manner that at the commencement of winding a bobbin the speed of rotation of the bobbin is greater and gradually decreases with the increase of the bobbin diameter so that the speed at which the thread is drawn off remains uniform.

From the shaft 39 of one of the cone pulleys, e. g. 33, through gears 40, 41 and worm gear 42 is driven a shaft 43 which through a reversing gear 44—44a rotates the afore said screw spindle 37 alternately in opposite directions. A nut screwed on the spindle acts upon the aforesaid belt guide 38 and at the same time upon an engaging member 45 which alternately strikes against abutments 46 and 47 which are adjustably secured on a slide rod 48. By this abutment the rod 48 is carried a short distance to the left or right, whereby by means of an arm 49 it releases a cam-shaft 50 for a half revolution and this effects a series of reversing movements.

A shaft 53 journalled in the interior of the hollow cam-shaft 50 is constantly driven from the shaft 24 by means of worm gears 51—52 and tends constantly to take with it

the hollow cam-shaft 50 by means of a friction coupling 54, in clockwise direction in Fig. 1. This coupling is composed of a part connected with the shaft 53, and a part connected with the shaft 54, and the parts are frictionally engaged. A projection 55 on the driven portion of the friction coupling 54, that is, the part connected with the shaft 53 is however caught alternately by an abutment 56 and an abutment 57 of the arm 49. In the case illustrated the abutment 56 holds the projection 55 fast. The parts of the coupling 54 slide relatively to one another. This continues until the abutment member 45 strikes 15 against the abutment 46 and thereby moves the slider 48 to the left. (Figures 4 and 5.) In consequence of this the projection 55 is released, the shaft 53 rotates 180° in an anti-clockwise or reverse direction and then again 20 stops still because in the meantime the abutment 57 as it moves to the left with the rod 48 has come into the path of the projection 55. During this half-rotation a series of reversing movements takes place, the shaft 53 being 25 carried with the shaft 50 for a half rotation in one direction, and being moved in the reverse direction by a spring 54a. When the shaft 50 moves with the shaft 53 in the direction of the arrow in Fig. 4, the spring 54 is 30 tensioned.

The displacement of the arm 49 acts through rod 58, and a cooperating lever 59 upon a movable portion 60 of the coupling 44-44a so that the direction of rotation of the screw spindle 37 is reversed and the nut with the part 45 now moves from left to right in the direction towards the abutment 47. The coupling 44-44a is constituted by a pair of oppositely arranged bevel gears loose on 35 the shaft 43. The element 60 is adapted to couple either to the shaft 43, said element 60 being splined on the shaft. Both gears 44 and 44a mesh with a gear 37a on the screw rod 37. The element 60 is shifted by means 40 of a lever 59, pivoted at 59a to the frame, and having a fork rotatably engaging the element 60. A cam plate 60a is secured to the lever, and the said plate has a diagonal slot 60b, as shown in Fig. 8. A pin on the rod 58 45 engages the slot, the pin 58a having a roller as shown, and it will be apparent that when the rod is moved in either direction, the lever 59 is swung, to couple one of the gears 44-44a to the shaft 43. Cam discs 61, 62 mounted on 50 the shaft 50 act upon the cam levers 63, 64 of the friction couplings 65, 66 arranged on the shafts of the cone pulleys 33, 34 in such manner that instead of the pair of pulleys 28, 33 55 which were formerly driven, the pair of pulleys 32, 34 now sets into rotation the spindles 13 or 14 which are situated in the engaging position. At the same time the actuating shaft 50 acts upon a reversing shaft 69 60 through a pair of bevel wheels 66, chain drive 65

67 and a toothed gear 68, which shaft 69 runs through all the boxes 11.

Until the described moment of reversal the coupling 65 on the shaft 39 of the pulley 33 was engaged and the pulley was thereby 70 coupled with the pinion 70, which through suitable intermediate wheels 71, 72, 73 rotated the shaft 74 journalled below the spindle box 11. The shaft 74 has in each box 11 a worm 75 which is in engagement with a corresponding worm wheel 76 of the spindle 13 situated in the operative position, and in consequence of this the bobbins 15 of all the spindles 13 are driven and the speed thereof determined, as described by the position of the driving belt 80 of the pair of cone pulleys which is in action. The reversing shaft also has in each spindle box a worm 77 which engages with a worm wheel 78 which is rigidly connected with the two covers 16 of the appurtenant box. At the 85 moment of reversal the shaft 69 is driven through the gear 66, 67, 68 from the actuating shaft so that the worm wheel 78 executes a half-rotation. The wheels 76 of the spindles 13 thereupon come out of engagement with the driving wheels 75 of the shaft 74 and in their places the similar worm wheels 79 of the spindles 14 come into engagement with the worms 75, so that now the spindles 13 with the full bobbins 15 stand still and the 90 empty bobbins 15 of the spindles 14 are driven. At the same moment, as described, the coupling 65 is thrown out and the coupling 66 of the shaft of the cone pulley 34 is thrown in. Now the shaft 74 is driven from 100 this shaft over the wheels 80, 81, 71, 72, 73. This operation continues until the abutment 45, which now moves towards the right, strikes against the abutment 47, moves the abutment 57 out of the path of the projection 55 and therewith effects a further half-rotation 105 of the actuating shaft 50.

The thread is guided from the spinning nozzle 82 over the thread guide 83 to the bobbin 15 situated in the operative position. 110 With the direction of rotation of the discs 16 and the bobbins 15 indicated by arrows in Fig. 1, the winding up of the thread on the fresh bobbins which have now newly reached the operative position and are being driven takes place without further ado. The to and fro motion of the thread guide 83 is effected by means of the oscillating arm 84 of a rotating shaft 85 which is rotated to and fro from the driving gear of the device in a manner not 115 illustrated.

As is readily apparent, when the part 45 strikes against the abutment 47 the operation described is repeated, i. e. the rotation of the screw spindle 37 is reversed, the coupling 66 again thrown out and the coupling 65 therefore again thrown in. The spindles 13, on which empty bobbins 15 are now mounted, again reach the operative position and the full bobbins of the spindles 14 come to a 120 125 130

standstill. By the adjustment of the abutments 46, 47 the length of the thread which at any time is delivered on the bobbins can be secured in desired manner.

Having now particularly described and ascertained the nature of my said invention and in what manner the same is to be performed, I declare that what I claim is:—

1. In a spinning machine for artificial silk, a driving gear, two sets of rotating bobbins, means for alternately connecting one of the sets of bobbins with the driving gear, an actuating shaft positively and automatically actuating the said connecting means, an abutment member constantly moved to and fro longitudinally by the said driving gear, stops adjustable toward and from each other for controlling the connecting means and initiated to operate said means by engagement of the abutment member with the stops.

2. In a spinning machine for artificial silk, a driving gear, two sets of rotating bobbins, means for alternately connecting one of the sets of bobbins with the driving gear, an actuating shaft positively and automatically actuating the said connecting means, an abutment member, a gear train constantly imparting a to and fro movement to the said abutment member deriving its motion from the said driving gear, adjustable stops operatively connected with the connecting means and cooperating with the said abutment member, means for operating the said connecting means upon impact of the abutment member against the said stops, and means for reversing the driving direction of the said gear train upon each cooperation of the said abutment member and stops.

3. In a spinning machine, a pair of bobbin supporting shafts, a swinging support in which the shafts are journaled, means to rotate the shafts, driving mechanism, means operated by the driving mechanism at selected intervals for swinging the support to bring the shafts in alternation into engagement with the rotating means, and means between the driving mechanism and the rotating means to cause a gradual decrease in the speed of rotation of the bobbin supporting shafts after they are brought into engagement with the rotating means.

4. In a spinning machine, a pair of bobbin supporting shafts, a swinging support in which the shafts are journaled, means to rotate the shafts, driving mechanism, means operated by the driving mechanism at selected intervals for swinging the support to bring the shafts in alternation into engagement with the rotating means, and means between the driving mechanism and the rotating means to cause a gradual decrease in the speed of rotation of the bobbin supporting shafts after they are brought into engagement with the rotating means, said last named means including oppositely arranged pairs of coni-

cal pulleys, the members of the pairs being oppositely arranged, belts connecting the members of the pairs, and a common belt shifter operated alternately in opposite directions by the driving mechanism, and means operated by said mechanism for alternately coupling corresponding members of the pairs to the rotating means.

5. In an artificial silk spinning machine, including alternately rotating spindles, and a reversible spindle carrier to bring the spindles in alternation into rotating position, means to rotate the spindles at a speed gradually decreasing as the yarn is wound thereon, means to reverse the carrier at selected intervals, and means to coordinate the operation of the reversing means and the speed slowing means, so that an unwound spindle will be in position to be rotated when the rotating means is at its highest speed.

In testimony whereof I have affixed my signature.

HERMANN HAMEL.
